UNITED STATES PATENT OFFICE.

REUBEN RULAND SHAFTER, OF NEW YORK, N. Y.

TUBULAR TRITURATING-MILL.

No. 926,441.

Specification of Letters Patent.

Patented June 29, 1909.

Application filed May 13, 1908. Serial No. 432,629.

To all whom it may concern:

Be it known that I, REUBEN RULAND SHAFTER, a citizen of the United States, and a resident of the city of New York, borough of Manhattan, in the county and State of New York, have invented a new and Improved Tubular Triturating-Mill, of which the following is a full, clear, and exact description.

10 This invention is an improvement in tubular triturating mills of the character which contain a quantity of pebbles, spheres or other like pulverizing elements. In machines of this nature the material to be 15 ground is introduced into the grinding tube or drum having the pebbles, and as the drum revolves the pebbles roll upon each other and reduce the material to powder. I have discovered that in these machines substantially 20 the entire pulverizing action takes place at the surface by the rolling of the pebbles from one side of the drum to the other as the latter revolves. As these pebbles are considerable 25 in weight when the drum is filled to the height to obtain the best results, which is generally about half full, the power necessary to drive the mill is materially increased. It is my aim to get rid of the large percent. of the dead weight of the pebbles and the disadvantages entailed by their use, and at the 30 same time increase the grinding capacity of the mill, which I do by placing in the drum a stationary body to fill the space ordinarily occupied by the center mass of pebbles, the 35 body preferably providing an annular space between it and the drum for the passage of the pebbles, and having a flat top face inclined to the horizontal at an angle substantially equal to the angle of repose of the 40 triturating mass, with the high edge of the body located adjacent to the side of the drum moving upwardly, whereby the pebbles and the material being ground will be drawn through the annular passage by the 45 revolution of the drum, and will roll down the inclined upper surface of the body to the opposite side of the drum and thus reduce the material to a powder.

Reference is to be had to the accompanying drawings forming a part of this specification, in which similar characters of reference indicate corresponding parts in all the views.

Figure 1 is a central vertical longitudinal section through a tubular grinding mill em-

bodying my invention; Fig. 2 is an end view 55 of the same; Fig. 3 is a cross section through the tube or drum; and Fig. 4 is a fragmentary sectional view of a drum having a modified form of lining.

Revolutionally mounted in suitable supports 5 60 are the hollow gudgeons 6 formed on the opposite end heads of a tube or drum 7 which is preferably made in two longitudinal half sections joined together at one side by hinges 8, and at the opposite side adapted to be 65 locked in closed position through eye-bolts 9 by any suitable means. The drum is made up of a metal jacket having a lining of vitrified brick or other suitable material 10, as is the customary practice in mills of this character. These bricks may all be laid flat, as shown in Fig. 3, or alternately stood on ends; as in Fig. 4, as desired, in the latter case the projecting portions of the brick stood on ends operating to draw the triturating mass 75 around with the drum as the latter revolves.

Within the drum I provide a body 11, which is the primary feature of my invention, said body being preferably hollow in order to insure lightness, and extends longitudinally of 80 the drum almost its full length. The body in its preferred form is approximately semi-circular in cross-section and arranged concentric or slightly eccentric to the drum, providing an annular passage therebetween. 85 The flat face of the body is arranged at the top at an angle approximately equal to the angle of repose of the triturating mass, with the elevated edge of the said top located adjacent to that side of the drum moving upwardly. 90 The top face of the body is preferably provided with a number of longitudinally arranged upwardly projecting plates 12, between which is placed a layer of brick forming the top face of the body which is arranged slightly below the top of the plates 12. The body at its forward end connects with a feed tube 13 having a feed hopper 14, and in which a spiral conveyer 15 is revolutionally 95 mounted; and at the opposite end the body 100 connects with a discharge tube 16, which, like the feed tube 13, passes through one of the gudgeons of the drum and is stationarily fixed concentric therewith in any customary or approved way. The discharge tube also 105 passes through a perforated plate 17, at the inside of which it is provided with an opening 19 for receiving the pulverized material.

One of the sections of the drum is constructed with a manhole which is normally covered by a removable cap 20. Through this hole a limited access may be had to the interior of the drum for repairs and other purposes; or if it is desired to get between the body and the drum, as when placing in or renewing the lining, the two sections of the drum are unlocked and swung apart on their hinges. For revolving the drum I have shown the usual mechanism, which consists of a gear 21, in mesh with a smaller gear 22, carried on a shaft 23, which is provided with a driving pulley 24, the gear 21 being rigidly attached to the drum near one end, this special construction, however, forming no part of my invention, as the drum as well as the spiral conveyer, may be driven in any approved way.

In the drum is placed a sufficient quantity of triturating elements 25, to fill the annular space between the hollow body and the lining of the drum, and substantially cover the upper surface of the body. The conveyer and drum are set in motion, and the material to be ground is introduced into the hopper 14. As the drum revolves, the triturating elements, together with the material, are carried around through the annular passage and roll down the top inclined face of the body, a layer of the pebbles being caught and held by the projecting top edges of the plates 12, and the layers of pebbles above them roll or slide over these pebbles and pulverize the material in passing to the opposite side of the drum.

It will be noted in Fig. 3 that the top face of the hollow body is not exactly a plane surface but curves upwardly as the lower edge is approached. I construct the body in this manner for the reason that after the pebbles begin to roll and acquire sufficient velocity, it is unnecessary that the angle which the face of the body makes with the horizontal be as steep, as it is desirable that the acceleration of the pebbles be checked preparatory to their passage again through the annular space. As the material becomes thoroughly pulverized it passes through the perforations of the plate 17 and thence out through the discharge tube 16.

While I have described the invention with some particularity, I nevertheless regard the precise embodiment as immaterial and consider that the invention is defined by the scope of the annexed claims.

Having thus described my invention, I

claim as new and desire to secure by Letters Patent:

1. A tubular triturating mill, comprising a revoluble drum adapted to contain a quantity of triturating elements, and a body fixed within the drum as a substitute for certain of said elements, and over and around which said elements are drawn by the revolution of the drum during the triturating operation. 60 65

2. A tubular triturating mill comprising a drum, an imperforate body fixed within the drum and arranged approximately parallel to the axis thereof, and a quantity of triturating elements within the drum, movable 70 around said body.

3. A tubular triturating mill comprising a revoluble drum, a body fixed within the drum extending approximately its full length and having an upper face inclined laterally 75 with respect to the axis of the drum, and a quantity of triturating elements within the drum, successively movable about and over the upper face of the body during the revolution of the drum. 80

4. A tubular triturating mill, comprising a revoluble drum adapted to contain a quantity of triturating elements, means for introducing into the drum, the material to be ground, and a body within the drum extending the major portion of the length thereof and around which said elements repeatedly pass when the drum is revolved. 85

5. A tubular triturating mill, comprising a revoluble drum having hollow gudgeons revolvably mounted and adapted to contain a quantity of triturating elements, a body within the drum, around which said elements travel when the drum is revolved, and a feed tube and a discharge tube supporting the opposite ends of the body and passing through said gudgeons. 90 95

6. A tubular triturating mill, comprising a drum adapted to contain a quantity of triturating elements, and a body fixed within the drum around which said elements are adapted to pass, said body having an inclined upper face, with the upper portion arranged at a greater inclination than the lower portion. 100

In testimony whereof I have signed my 105 name to this specification in the presence of two subscribing witnesses.

REUBEN RULAND SHAFTER.
